UNITED STATES PATENT OFFICE.

ALBERT HARRY WHEELER, OF WORCESTER, MASSACHUSETTS.

BLANK FOR FORMING HOLLOW POLYHEDRONS.

1,292,188.

Specification of Letters Patent. Patented Jan. 21, 1919.

Application filed March 4, 1918. Serial No. 220,202.

To all whom it may concern:

Be it known that I, ALBERT HARRY WHEELER, a citizen of the United States, residing at Worcester, in the county of Worcester and State of Massachusetts, have invented a new and useful Blank for Forming Hollow Polyhedrons, of which the following is a specification.

This invention relates to the construction 10 of polyhedrons of sheet material in a simple and convenient way for the purpose of demonstrating principles of solid geometry in the classroom and for similar purposes.

The principal objects of the invention are 15 to provide a construction of a blank from sheet material, as for example, paper which can be manipulated in a certain way so as to produce a hollow polyhedron; to provide constructions connected therewith for effect- 20 tively holding the parts together at the angles, and of such a nature that no projecting parts come outside the hollow figure when it is completed, thus producing a new article of manufacture in the polyhedron 25 itself; and to provide an improved hinge connection for pivotally joining two pieces of sheet material so that the blank need not be formed of a single piece, but can be formed of several if desired. This construc- 30 tion is also capable of use independently of the production of polyhedrons. Further objects and advantages of the invention will appear hereinafter.

Reference is to be had to the accompany- 35 ing drawings, in which—

Figure 1 is a plan view of a blank shown in three pieces for forming a regular dodecahedron;

Fig. 2 is a plan of one end of said blank 40 showing some of the adjacent faces as secured in position to illustrate the manner in which the blank is manipulated to start to form the solid figure, the faces of the blank not yet connected being broken away;

Fig. 3 is a view similar to Fig. 2 showing 45 in direct plan a half of the figure completed and the remainder of the faces also connected together to form the other half of the figure but being bent off to one side 50 so as to give a view of the interior of the first mentioned half and showing the way in which the faces are held in position at the angles;

Fig. 4 is a view of a complete dodeca- 55 hedron in front elevation;

Fig. 5 is a view similar to Fig. 1 of a blank arranged for forming an irregular polyhedron formed of six square sides and eight triangular ones;

Fig. 6 is a front elevation of the com- 60 pleted polyhedron which is in reality a cube with the six corners truncated in a regular manner;

Fig. 7 is a fragmentary view of a pair of 65 faces or sheets showing a modified form of hinge, and

Fig. 8 is a similar view showing another form.

In the form of the invention shown in the first four figures a blank is provided con- 70 sisting of three pieces A, B, C. Each one of these pieces, and in fact the entire blank is made up of a plurality of regular polygons, in this case pentagons, each one destined to constitute one face of the dode- 75 hedron shown in Fig. 4. It is to be understood that this blank can be all in one piece as shown in Fig. 5, but three pieces are illustrated here for convenience.

For the moment, ignoring the manner of 80 connecting these three pieces and assuming them to be all connected so that they act as a single sheet, all the twelve faces of which are integral with each other and constitute a continuous series, it will be seen that 85 each of these faces is connected with the next one along a straight line which constitutes one of its edges. These connections are integral except in two places in the form illustrated and they all constitute hinges 90 about which the faces can be bent with respect to each other. It will be seen also that each of the faces is provided with either one or two projecting holding or fastening tabs D.

It is to be observed that, each of the 95 angles of the pentagon being one hundred and eight degrees, the several angles d , that is the obtuse angles formed between the adjacent edges of the polygon face and the respective tabs D are shown the same, that is one hundred and eight degrees in order to form a contact with the inside face of the next face. This gives a maximum holding force but it is to be understood that these 100 angles can be smaller so long as the distance between the two tip ends of a tab is greater than the length of the corresponding edge of the polygon. The location of these several tabs is such that either the ends of two 105

95

100

105

110

tabs on one face or the end of one tab on one face and of another tab on the next face are located at the opposite ends of each of the hinged edges of the polygon.

5 I have numbered the several polygons of this figure from 1 to 12 inclusive, indicating the order in which they can be folded up although the figure can be constructed in the reverse order. Face 1 can be considered 10 as the base of the dodecahedron to be produced. In order to form the figure the face numbered 2 is turned up out of the plane of the base 1 and brought of course to the necessary angle which need not be stated 15 or calculated because the configuration of the parts is such that it will not lock in position at any other angle. This is the only thing necessary at that time. This having been accomplished the face numbered 20 3 is bent about its hinge connecting it with face 2 to the position in which it makes the same angle with the base as face 2. In doing this it will be observed that the tab D' on face 1 is brought up inside face 3 25 and the location of this face, in the form shown, in position with its lower edge contacting with the horizontal edge of the base 1 causes this tab D' to hold the above mentioned position with a maximum of efficiency. Now the tab D⁴ on the next face 30 at the bottom, which just before the last motion mentioned had to be folded back against the inside of the face, can now be brought out into horizontal position on the base 1 and the face D⁴ swung around until its lower edge contacts with the third edge of the base. Now face 5 is brought 35 up in the same way against the other tab D₁, on face 1 and face 6 is brought around 40 and its tab D⁶ is also brought into horizontal position and the faces are locked in that place by bringing the tab D² inside of the face 6, so that its lower edge which is now horizontal projects over the tab D⁶ 45 and holds it in horizontal position. The tab D⁴ holds the tabs D¹ and D₁ up in their inclined positions against the inside surfaces of their respective faces 3 and 5, this tab D⁴ being horizontal and in contact with 50 the base 1. The reason for making the angles α one hundred and eight degrees will now be apparent. The end edges of all the tabs D¹, D₁, D⁴ and D⁶ fit against faces or tabs that at their margins have to make 55 this angle with the adjacent faces in the form shown in Figs. 1 to 4.

These six faces are now in the position shown in Fig. 3 in plan. That figure is a little misleading because the other half of 60 the solid figure is not made usually independently but the figure is made progressively all the way in accordance with the numbering on the faces. It is shown merely in this way for illustrating where the faces 65 and tabs are located when the figure is half

done and it incidentally shows certain things about the rest of the figure. It is true, however, that the whole dodecahedron can be shown as constructed in that figure and then the parts united.

Now the face 7 is bent inwardly toward the center of the figure in ordinary construction, and its tab D⁷ locked in between the two tabs D² and D₂, and the rest of the figure is formed progressively as stated until 70 the last side numbered 12 is brought into position and there the last tab D₁₂ is tucked in behind the edge of the tab D₁₀ at one end and the tab D₉ at the other to complete the figure. We get the dodecahedron as 80 shown in Fig. 4 in which it will be seen that there is no indication outside that there is any fastening means for holding the faces together, all the tabs being concealed inside. This is one of the objects of the invention 85 and renders the resulting product a convenient one for use for demonstrating purposes, but it will be seen that in spite of the concealment of the fastening tabs they thoroughly fasten the parts in position on account of their angular relation to the faces and length.

I might remark at this point that this identity in angles is not necessary even when the regular polyhedron is constructed and 95 would have to be modified in case of an irregular polyhedron. I have shown the tab D₁₂ as made of two pieces to facilitate bending it to complete the figure.

In the first four figures I have shown the 100 pieces A and C separately hinged to the piece B by a hinge construction. In this case the hinge construction consists simply of two hinge tabs E extending from each of the faces, each tab being shown as of a 105 general rectangular form and having a space E' separating them. Immediately under each tab E at one edge there is a slit e. These slits are for receiving the corresponding tabs on the other face. The distance 110 from the solid left end E' of the right hand tab E to the opposite end of the left hand slot e adjacent to it on the face 10 is equal to the length of the line by which the left hand tab E is connected with the face 11, 115 and the same relationship is true of course for the other tabs. Therefore in putting these tabs together when the two faces are placed back to back they can be slid together in the plane, being first folded on each other 120 until the back of the tab E on the face 10 substantially coincides with the corresponding line, that is the line e' on the tab on the face 11. This requires no bending or distortion of the faces at all. Now if the 125 two faces 10 and 11 are folded upon each other through any angle whatever, it will be found that these two edges e' will slip by each other and we have a hinge connection, but one that will not separate with- 130

out tearing or very badly distorting the parts unless the two faces 10 and 11 are folded together in contact, in which case the two edges e' can, if not naturally past each other, be brought past each other and then the two parts slid by with a transverse sliding motion. It is to be noted that the angle between the line between the tab E and the member 10, that is the line on which 5 it is hinged, and the edge e' is greater than the one the hinge line makes with the edge of the slot E which happens in this case to be zero. This shows up better in Fig. 7 where the latter angle is an acute one. 10 This furnishes a stop to prevent the parts separating in all positions of the two sheets which are hinged together except the one in which they are turned over into contact with each other. 15 In Figs. 7 and 8 other forms of hinge are shown embodying the same principles. In Fig. 7 these principles are shown but in such form that the tabs F are without any slits but are simply made in the form of a trapezoid, in which the principles set forth above 20 are carried out, the parts being assembled and taken apart in the same way as above described.

In Fig. 8 the tabs G are made in different 30 form, but the relative dimensions and arrangements are the same as in Fig. 1, only the tabs instead of being the same length are formed one long and the other short, and they are shown as cut away near the center 35 simply to avoid the presence of surplus material.

In Figs. 5 and 6 the construction of an 40 irregular polyhedron is shown, the faces of the same being made up of squares and triangles, and in this case the tabs are shown provided with end angles of sixty degrees the same as those of the triangular faces. This blank also is different from the one 45 shown in the first four figures, because the parts are all one integral whole, but that is not a feature peculiar to this figure as the same thing could be accomplished with the form shown in those figures. For that reason this construction will not be described 50 in detail.

Although I have shown the invention as applied to one particular regular polyhedron and one irregular one I am aware of the fact that it can be applied to the construction 55 of various regular and irregular polyhedrons without change in principle, only such changes in the angles and relations as are necessary to provide for different shapes.

Although I have illustrated and described 60 only certain definite forms of the invention I am aware of the fact that modifications can be made therein by any person skilled in the art without departing from the scope of the invention as expressed in the claims. 65 Therefore I do not wish to be limited to the

construction of any definite figure or to all the details of construction, but what I do claim is:—

1. A blank of sheet material for use in constructing a hollow polyhedron, said blank being shaped to provide the number of polygonal faces necessary to produce the desired shape, said faces being flexibly connected with each other in a continuous series, the line of connection in each case being 75 along one of the edges of the face, said faces having flexibly connected tabs extending beyond the boundaries of the respective polygons at the ends of said lines of connection to hold the faces together. 80

2. A blank for use in producing a polyhedron made up of a number of polygonal faces, each connected to another one along an edge by a flexible connection constituting a hinge, and a projecting hinged tab at 85 each end of the hinge, each tab being adapted to fit against the surface of an adjacent face when the figure is completed to hold the faces in position.

3. A blank of sheet material for use in 90 constructing a hollow polyhedron shaped to provide the number of regular polygonal faces necessary to produce the desired shape, said faces being flexibly and integrally connected with each other in a continuous integral series along the edges of the faces, and tabs flexibly connected with the several faces and having ends extending beyond the ends of the faces for the purpose of folding inside the adjacent faces and holding them in position. 95

4. A blank of sheet material for use in constructing a hollow polyhedron comprising the number of polygonal faces necessary to produce the desired shape, said faces being flexibly connected with each other, said faces having flexibly connected tabs extending beyond the boundaries of the respective polygons at the ends of the lines of connection, certain of said tabs having their ends 105 projecting beyond the line with which they are connected to the face so as to fold in behind an adjacent face. 110

5. A blank for use in producing a polyhedron made up of a number of polygonal faces, each connected to another one along an edge by a flexible connection constituting a hinge, one or both of each two adjacent faces having a projecting hinged tab at the end of the hinge adapted to fold behind the 115 inner surface of an adjacent face when the figure is completed, to help hold the faces in position, one of said tabs having its ends forming projections located a distance apart greater than the length of the hinge line at 120 the edge thereof by which said tab is connected with the adjacent faces. 125

6. A blank of sheet material for use in constructing a hollow polyhedron, shaped to provide the number of polygonal faces 130

- necessary to produce the desired shape, said faces being flexibly connected with each other and having flexibly connected tabs extending beyond the boundaries of the respective polygons at the ends of the lines of connection, one of said faces being separably connected with another and adapted to swing about the separable connection as a hinge. 5
- 10 7. A blank for use in producing a polyhedron made up of a number of polygonal faces, each connected to another one along an edge by a flexible connection constituting a hinge, said hinge comprising two tabs extending from each face, said tabs being separated from each other and having a space for the reception of a tab on the other face, means whereby the two faces when in contact with each other can be moved together 15 by a motion in a plane until the rear ends of the respective tabs come into contact and pass each other and then the two faces will be hingedly connected with each other, one or both of each two adjacent faces having 20 a projecting hinged tab at the end of the hinge adapted to fit against the surface of an adjacent face when the figure is completed to help hold the faces in position. 25
8. A body of sheet material comprising 30 two members or faces each of them having two tabs projecting therefrom in the plane thereof, the space between the two tabs on each one, along the straight boundary line between the member and the tabs, being 35 equal to the length of a tab on the other piece so that the two members can be united by placing them in contact and moving them together with the forward edge of each tab guided behind the adjacent edge of the corresponding tab on the other member until 40 the rear edge of the forward tab on each member coincides with the rear edge of the tab on the other member and whereby the two members are thus hinged together and inseparable from each other without tearing or bending the same, at all times except when they are brought back in the same plane and into contact with each other. 45
9. As an article of manufacture, a body comprising two parts of sheet material having a hinged connection with each other, provided with means for inseparably joining them in all positions except one and readily separable without bending when in that one position. 50
10. A hollow polyhedron closed on all sides formed of sheet material and provided with fastening means located entirely inside it at the ends of some of its edges and constituting continuations at the ends of some 55 of its edges. 60
11. As an article of manufacture a body comprising two parts, formed of sheet material, having a hinge connection between them comprising two tabs on each one, the body of each tab being longer than the neck which joins it to the main part of the sheet material, said tabs on each part being spaced apart to permit the entrance between them of a tab on the other part. 65
12. As an article of manufacture, a body comprising two parts, formed of sheet material, having a hinge connection between them comprising two spaced tabs on each, the body of each tab being longer than the neck which joins it to the main part of the sheet material, the corresponding edges of said tabs being parallel and one of each having an edge crossing a corresponding edge on a tab of the other part and located 70 at an angle to the outer edges of the sheet and constituting a stop to prevent their separation, except when the two parts are folded back into contact with each other. 75
- In testimony whereof I have hereunto affixed my signature. 80
